UNITED STATES PATENT OFFICE.

HAROLD GIBSON, OF OMAHA, NEBRASKA.

ACCOUNT-BOOK.

1,160,276.

Specification of Letters Patent. Patented Nov. 16, 1915.

Application filed April 21, 1913. Serial No. 762,445.

To all whom it may concern:

Be it known that I, HAROLD GIBSON, a citizen of the United States, residing at Omaha, in the county of Douglas and State 5 of Nebraska, have invented certain new and useful Improvements in Account-Books, of which the following is a specification.

This invention relates to a combined time book and job record, particularly adapted 10 for use in connection with machine shops or the like, where labor expended in repairing articles belonging to others is paid for by the hour, and charges against the owners of the articles are based on the number 15 of hours required in making repairs.

In carrying on the business of manufacturing establishments and repair shops it is customary for the proprietor when making charges for construction or repairs, to enter 20 the items of debits at the actual cost of labor and material with a percentage of profits added. The account and its several items, therefore, should be such that either a debtor or creditor may conveniently inspect 25 and find the items.

The object of the invention is to provide a book so arranged that a record for specific periods may be kept to show, in compact form, time-credit entries for the employees, 30 identification of the several employees; and separately, to show identification of the debtors or parties for whom the work was performed, and to provide a record showing the time specifically expended for each 35 debtor on each job or contract and the names of the workmen who performed the service therefor and dates when performed, and which will provide a means for proving accuracy of the accounts, and exhibit totals of 40 all of the items for each of the periods; also since more than one order may be given by the same individual during a single period, the account book herein described provides for the numbering of all of the orders, so 45 that no confusion may arise.

With the foregoing objects in view and others to be mentioned herein, the invention consists of the novel combination and arrangement of parts as will now be described and claimed, and as illustrated in 50 the drawing wherein,—

Figure 1 is a perspective view of an account book embodying my invention. Fig.

2 is a view of one of the half-width sheets, being the reverse side view to that shown 55 in Fig. 1. Fig. 3 is a broken view showing a part of the last page of one of the specific periods. Fig. 4 is an end view of the account book when closed.

Referring now to the drawing, the leaves 60 of the account book shown in Fig. 1 are arranged in series, each series being for a specific period of time, and comprising a first page *a* of a leaf *a'*, a last page *b* of a leaf *b'*, and a plurality of intermediate half-width sheets identified as *c*, *d*, *e*, *f* and *g*, each of the half-width sheets being formed, preferably, with an outwardly-projecting upper corner *h*, provided with a short horizontal line as shown, for entering thereon 70 the day, month and year. While this arrangement provides time-periods for a week, so that any date may be readily found, other uniform periods of time could be provided, if desired.

All entries for one day may be made, in part, upon any one of the pages of the half-width sheets and upon the adjacent page of a succeeding half-width sheet. For the first working day of the week as, for instance, 80 Feb. 3, 1913, the entries may be made, in part, upon page *a* of leaf *a'* as shown in Fig. 1, and upon the adjacent page *c* of sheet *c* shown in Fig. 2; and for the last working day of the week, shown in Fig. 1 85 as Feb. 8th, 1913, the entries may, in part, be made upon the last page of the half-width sheet *g* and, in part, upon page *b* of sheet *b'* as shown in Fig. 3. The pages thus mentioned are provided with horizontal lines *i* 90 and vertical lines *j* which intersect to provide spaces *k* for entering credits for the number of hours of work performed by the employees, and upright lines *l* are provided and connected with the vertical lines to provide spaces *m* for indicating the names of persons who ordered the work and who, therefore, would become debtors when their contracts were completed.

At *n* are indicated horizontal, double or 100 "sight-lines" provided for all of the pages, and above the upper sight-line and intersected by lines *j* is a horizontal line *o* to provide spaces *p* for entering the numbers of the orders, this being necessary since 105 more than one order may be given by the

same individual and that the work performed on each order may be kept separately and identified.

The first page is provided with two vertical columns *q* and *r* for the entry therein, respectively, of the names of employees and their corresponding numbers. For keeping an account of the amount of labor expended upon each order, the number of hours each 10 employee has worked each day on a particular job is entered in the spaces *k* which appear horizontally opposite the names of the employees, and vertically below the order. At the bottom of each page is provided a horizontal double-line *s*, and below this line the totals are entered showing all of the hours of work performed on each contract, each day. It will thus be seen that an 15 account may be kept in compact form showing how many hours should be charged against each order, also identifying the employees who performed the work, and at the same time crediting them with their labor. This 20 greatly simplifies the work of book-keeping and provides a convenient record for reference. For instance the record shows that job or contract Number 1 entered on page *a* is charged to Jno. Jones, and that on Feb. 3rd, 1913, four hours work 25 was performed by employee Jackson No. 1; six hours by Williams, No. 4; eight hours by Mason, No. 9; and 4 hours by employee Manning, No. 10; and at the bottom of page *a*, the amount 22 appears, showing the total 30 number of hours for one day of work done on this contract. Likewise it appears that on the same date nineteen hours of work was performed on contract No. 2 for Wm. Smith, the employee being Johnson, Hoffman and Larson, the respective number of 35 hours for each being 8, 7 and 4. Fig. 1 shows the names of other employees in column *q*, together with certain hours credited in spaces *k* with labor, and the 40 names of others inserted in spaces *m* who have given orders for work, on different days for the week ending Feb. 8th, 1913, these items appearing on pages *a* and *b* and on the half-width sheets, but these additional 45 entries require no explanation since it will be understood that, for all contracts entered into during the period, the names of the parties ordering the work to be performed are entered in spaces *m* as debtors and numbered in spaces *p*, the entries being 50 made on the dates given, and the credits to the workmen being also given each day.

Provision is made for verifying the accuracy of the account for labor, and for this 55 purpose, in part, a summary diagram *t* is provided at the right side of page *b* consisting of lines *u* disposed in alinement with lines *i* of pages *a*, *b* and with the horizontal lines *i* of the half-width sheets, and vertical

lines *v* are provided which intersect lines *u* 65 to form spaces *w* and thereby providing vertical columns for the entry therein of the total number of hours of work performed by each workman for each day of the period. At the head of each of these 70 columns in said diagram the days of the week may be suitably designated as shown in Fig. 1, and by entering the totals of the number of hours which have been entered, the account may be proven since a comparison 75 may be made of the sum of these totals with the total number of hours found at the bottom of the several pages. The summary diagram may also be used for keeping an account of the rate per hour 80 paid to the workmen, amount earned by them and amounts advanced and paid to them for labor performed, as indicated by vertical columns *x*, *x'* and *y*, *z*, and the totals of these items may be entered at the 85 foot of these columns.

Among some of the advantages to be derived by use of the herein described account book it may be stated, that with reference to any dispute which may arise between a 90 proprietor and a debtor as to the number of hours employed in work, the fact that the particular work was paid for by the hour to the workman, and the fact that the record discloses the name of each workman and 95 the number of hours devoted to each job or contract, ought to be conclusive as to accuracy; and the account is in such shape that all of the items for proving its accuracy are assembled in compact form, this 100 being a matter of convenience when referring to it as a record, and when entering the items.

Having fully described my invention, what I claim and desire to secure by Let- 105 ters Patent is,—

A combined time book and job record for specific periods, comprising, in combination with a leaf provided at its top with a horizontal margin and intermediate its bottom and horizontal margin with horizontal lines, and having a vertical margin adapted to bear the names of employees and provided with a horizontal line near its top for bearing a date of the specific period 110 and a plurality of vertical lines intersecting the horizontal lines to form spaces opposite the names of the employees, said leaf being provided in its horizontal margin with parallel lines disposed inclinedly and 115 connected with the vertical lines of said leaf, secondary leaves each having an outwardly projecting part adjacent to the junction of its vertical and upper horizontal edges provided with a horizontal line for bearing a 120 date of said specific period, and provided with horizontal lines adapted to register with the horizontal lines of the first named 125

leaf, each secondary leaf also being provided at its top with a horizontal margin and with vertical lines intersecting its horizontal lines to form spaces therebetween and provided at its horizontal margin with parallel inclined lines connected with the vertical lines thereof.

In testimony whereof I have affixed my signature in presence of two witnesses.

HAROLD GIBSON.
